UNITED STATES PATENT OFFICE.

SAMUEL HORELICK, OF PITTSBURGH, PENNSYLVANIA, ASSIGNOR TO PITTSBURGH TRANSFORMER COMPANY, A CORPORATION OF PENNSYLVANIA.

TRANSFORMER-BUSHING SUPPORT.

Application filed April 29, 1922. Serial No. 557,426.

This invention relates to electrical transformers and particularly to the supporting structure for the bushings insulating the electrical leads where they pass through the 5 transformer cover or other similar part. These bushings are of insulating material and since it is sometimes necessary to remove or replace them it is highly desirable that they be detachably mounted in place. At 10 the same time it is important that they be securely held in position and that the holding means be tightened against leakage of moisture into the interior parts of the transformer container and that the whole of the 15 structure be secure against deterioration due to weather conditions.

The object of this invention is to provide a supporting structure for a transformer bushing attaining the above results and at 20 the same time simple in formation and inexpensive in cost.

In the accompanying drawings the figure shown illustrates one embodiment of the invention in vertical elevation with parts 25 broken away and in section.

In the specific embodiment of the invention shown in the drawings the lead L from a transformer positioned in a tank passes upward through the insulating bushing B 30 and is connected to the top terminal T. A bushing or insulator support S surrounds the central portion of the bushing B and has a sleeve 5 extending up underneath the petticoat 6 and cemented to the bushing as indicated at 7. The flange portion 8 of the support S extends outwardly and is provided with a downwardly projecting annular flange 9 surrounding a circular seat portion 10 provided with a seal washer or 35 gasket 11. The gasket 11 sets on the top flange 12 of the cylinder or pipe 13 fitting within an opening of the top 14 of the transformer tank and welded thereto as indicated at 15. This cylinder 13 is simply a steel 40 plate rolled into cylindrical form and flanged as shown at 12.

The cylinder 13 is provided with a surrounding clamping ring 20 having a sleeve portion 21 slidably fitting the cylinder and 45 engaging under the flange 12 thereof. A flange portion 22 of the clamping ring 20 extends outwardly and is provided with bolt holes 23 alined with the bolt holes 24 of the flange portion 8 of the bushing support S. Bolts 25 are provided between the

flanges 8 and 22 and when these bolts are tightened the clamping ring 20 and bushing support S are drawn together with the clamping ring bearing under the flange 12 so that the gasket 11 is tightly pinched between the 60 flange 12 and the seat 10 of the support.

The cylinder 13 spaces the bushing supporting means away from the tank cover and the bushing extends freely above and below its support and is firmly held in position by 65 the cementing of its central portion within the sleeve 5. The outward extension of the flanges 8 and 22 position the clamping bolts 25 accessibly and at the same time permit the full clamping pressure of these bolts to 70 be directly transmitted to the parts gripping the gasket 11 and flange 12. None of the clamping or holding strains are transmitted to the insulating bushing B but all of these strains are concentrated in the supporting parts. At the same time the bushing support S is readily detachable to permit 75 removal and replacement of the bushing and all the parts are simple and rugged in structure adapted to provide a firm support and a permanently tight seal. 80

I claim:

1. In combination, a transformer tank having an opening, a hollow cylinder projecting therefrom and having a radial flange at its 85 outer end, an integral clamping ring slideable on said cylinder between said flange and said tank, means for permanently securing said cylinder and said tank together, thereby causing said tank, cylinder and ring to 90 be a permanent unitary structure, an integral support having a circular seat opposite said flange, a gasket between said flange and said seat, and means for pressing said clamping ring and integral support together thereby to press said flange and gasket between 95 said support and ring to form a tight seal, said integral support being adapted to have an insulating bushing rigidly secured thereto. 100

2. In combination, a transformer tank, a hollow cylinder projecting therefrom and having a radial flange at its outer end, a clamping ring slideable on said cylinder between said flange and said tank, said ring comprising an integral continuous circular member adapted to be positioned on said cylinder by being passed thereon only from the end thereof which is finally secured to the tank, means for permanently securing 105 110

said cylinder and tank together, thereby causing said tank, cylinder and ring to be a permanent unitary structure, an integral bushing support having a circular seat opposite said flange, a gasket between said flange and said seat, and means for pressing said clamping ring and bushing support together thereby to grip said flange and gasket between said support and ring to form a tight seal, said integral support being adapted to have an insulating bushing rigidly secured thereto.

3. In combination, a tank having an opening, a hollow cylinder having a flange at one end while the maximum diameter of the other end of the cylinder is smaller than that of the flange, an integral clamping ring assembled on said cylinder by being passed over the smaller end thereof, a weld for securing said smaller end and tank together, thereby causing said tank, cylinder and ring to be a permanent unitary structure, a

member adapted to support an insulating bushing and to cooperate with said flange to form a substantially leak-proof joint, and means cooperating with said support and ring to effect a clamping action for said joint.

4. In combination, a tank having an opening therein, a hollow cylinder having a straight end adapted to pass within said opening while the other end is provided with a flange, a weld for securing said cylinder and tank together, an integral ring positioned on said cylinder prior to said weld by being passed only over the straight end of said cylinder, a support adapted to carry an insulator bushing and cooperate with said flange to form a joint, and means cooperating with said ring and support for effecting a clamping action whereby a leak-proof joint may be had.

SAMUEL HORELICK.
